FIG.-4

Inventor:
Oto Zapp.

UNITED STATES PATENT OFFICE

OTTO ZEPP, OF OFFENBURG, GERMANY

HEATING BOILER

Application filed May 26, 1927, Serial No. 194,334, and in Germany January 25, 1925.

This invention relates to a heating apparatus of the kind composed of a plurality of hollow sections which are connected by pipes and assembled so as to form a furnace space between them, and the invention consists in forming the sections out of flat, hollow, rectangular bodies having lugs for supporting the furnace arches, the bodies being in communication with one another through two external pipe systems which divide the sections into two independent groups.

By this arrangement a very simple and efficient heating apparatus is obtained which can be extended to any required size, and the two groups of sections can be utilized in different manners, one group being employed for heating by means of hot water while the other is used for heating by means of low-pressure steam.

Fig. 1 of the accompanying drawings represents a side view of the apparatus partly in section,

Fig. 2, a transverse section of the same,

Fig. 3, a longitudinal section, and

Fig. 4, a horizontal section.

The heating apparatus is built up out of a plurality of shallow, independent, closed water vessels 1 which are made of cast or malleable iron in the form of parallelepipeds and assembled so as to enclose a space 5 which can serve as a furnace chamber for heating the vessels. For this purpose the vertically disposed vessels are adapted to support a tier of superposed refractory arches 6 on which the fuel, for instance coal dust, is placed for combustion. The arches are formed in known manner with upwardly tapering perforations 7 which are arranged in a staggered position relative to the perforations of adjacent arches.

Preferably the vessels are connected externally by pipes 2 and 3 into independent groups which can be used for heating simultaneously by means of hot water circulation, by means of low-pressure steam and by means of hot air. The hot air is obtained from outside the furnace, which for this purpose is enclosed in a chamber of masonry whence the air can be conveyed in known manner for utilization. The radiation may be promoted by

the provision on the boiler sections of vertical, radial gills 4.

One narrow side of the apparatus is fitted with a fire-door or doors, and the gases are led off from the top of the apparatus, the draught 55 and the combustion being regulated in known manner.

As an alternative to coal dust or the like, gas, oil or electricity may be employed as a heating medium.

I claim:

A heating apparatus of the character described, comprising a furnace chamber each side of which is composed of a plurality of flat, hollow rectangular boiler sections, external pipes connecting different sections into independent boiler systems, a plurality of sectional furnace arches arranged one above the other inside the chamber, and lugs formed on the inner sides of the boiler sections as 70 supports for said arches.
